UNITED STATES PATENT OFFICE.

THOMAS A. HOLLORAN, OF WASHINGTON, DISTRICT OF COLUMBIA.

APPARATUS FOR OPERATING ELEVATOR-DOORS.

1,112,009.

Specification of Letters Patent. Patented Sept. 29, 1914.

Application filed July 16, 1913. Serial No. 779,373.

To all whom it may concern:

Be it known that I, THOMAS A. HOLLORAN, a citizen of the United States, residing at Washington, in the District of Columbia, have invented certain new and useful Improvements in Apparatus for Operating Elevator-Doors, of which the following is a specification.

The invention relates to improvements in apparatus for operating elevator doors.

The object of the present invention is to improve the construction of apparatus for operating elevator inclosure doors, and to provide an exceedingly simple and inexpensive apparatus of strong and durable construction adapted to be applied to any elevator inclosure door or doors without requiring any increase in the clearance space ordinarily provided between the cars or cages and the walls of the elevator shafts and without necessitating any alteration in the construction of the cars or shafts.

A further object of the invention is to provide a door operating apparatus having door moving mechanism arranged sufficiently out of the way of the car and actuating mechanism on the car, and sufficiently out of the way of doors, sills and other parts of the elevator shaft to accommodate itself to the conditions ordinarily found in elevators such as shafts out of plumb, sills projecting different distances, doors set back different distances from the car, etc., and to enable the apparatus to be arranged on the car and in the elevator shaft in the most advantageous position for its convenient operation without impairing its efficiency in opening and closing the inclosure doors. In constructing elevators the specifications usually call for car clearance no greater than one and one half inches at the sills of the several doors and it is an object of the invention to provide a door operating apparatus which will work perfectly in the space surrounding the car in any elevator shaft.

Another object of the invention is to provide a door operating apparatus equipped at the several landings with independent door moving mechanism operated by a single motor carried by the car and adapted to actuate means on the car while the latter is stationary at the landings for imparting motion to the door moving mechanism, means being provided for effectually preventing the car from being started either up or down until the door or doors are

closed at the landing where the car has stopped.

Furthermore, the invention has for its object to provide an apparatus having door opening and closing mechanism which will admit of the door being moved by hand toward its closed position but which will securely lock the door against opening movement so that a door, should it be left open an inch or so may be closed by hand but will be prevented from being opened under such condition either by the operator or by any other person without operating the proper mechanism provided for the accomplishment of such result.

Another object of the invention is to prevent the accidents which frequently occur to persons entering and leaving elevator cars when the latter are stopped too far above or below the floors or landings by providing a door operating apparatus equipped with a construction operable only to open an elevator inclosure door when the car is stopped within perfectly safe limits of a floor or landing and thereby preventing a careless or inexperienced operator from stopping a car an unsafe distance from a landing and opening the inclosure door.

With these and other objects in view the invention consists in the novel construction, combination and arrangement of parts hereinafter fully described, claimed and illustrated in the accompanying drawings, in which—

Figure 1 is a perspective view of a door operating apparatus constructed in accordance with this invention. Fig. 2 is a vertical sectional view of the same taken transversely of the door. Fig. 3 is a vertical sectional view taken at right angles to Fig. 2. Fig. 4 is a detail perspective view of the locking device for holding the door in its closed position. Fig. 5 is a plan view of the motor. Fig. 6 is a diagrammatic view illustrating the manner of operating a double door. Fig. 7 is a detail horizontal sectional view illustrating the manner of guiding the traveler. Fig. 8 is an elevation partly in section of the apparatus showing a plurality of doors and door moving devices. Fig. 9 is a diagrammatic view showing the car operating circuit and the automatically operated switch.

Like numerals of reference indicate like parts in all the figures of the drawings.

The drawings illustrate one embodiment

of the apparatus for operating elevator doors, while the claims define the actual scope of the invention.

In the drawings in which is illustrated 5 the preferred embodiment of the invention 1 designates a slideable elevator inclosure door hung from a horizontal track 2 in the usual manner by hangers 3 having rollers 4 arranged to run on the said track 2. The 10 door is moved along the track to open and close it by door moving mechanism comprising an endless flexible connection preferably consisting of an endless chain 5, but a cord, cable or similar device may of course be 15 employed. The endless chain 5 is composed of horizontal and vertical portions guided by sprocket wheels 6, 7, 8 and 9 and forming upper and lower horizontal runs or stretches 10 and 11 and inner and outer vertical runs or stretches 12 and 13. The 20 horizontal runs or stretches 10 and 11 are located above the door 1, which is connected with one of them by an arm 14 formed integral with one of the hangers 3 and suitably secured to a link of the endless chain 5. In Figs. 1 to 3 inclusive the door 1 is connected to the upper run or stretch 10 but it may be hooked up to one or the other of the runs or stretches 10 and 11 according 25 to the arrangement of the door and when a pair of sliding doors 15 is employed at a landing as illustrated in Fig. 6 of the drawings one door is connected to one stretch or run of the chain 16 and the other 30 door is connected to the other stretch or run as the two stretches or runs of the chain 16 move in opposite directions and will simultaneously open and close the doors when motion is imparted to the chain 16. 35 One of the stretches or runs 12 and 13 of the vertical portion of the chain 5, preferably the inner stretch or run 12, is equipped with a support or member 17 carrying spaced upper and lower projections 18 and 40 19 coacting with and arranged to be engaged by motor actuated mechanism of a car or cage 20 to impart motion to the endless chain 5 for opening and closing the door 1. The support or member 17 which 45 may be constructed in any suitable manner extends across the space between the stretches or runs 12 and 13 and has a vertical guide 21 for the outer vertical stretch or run 13 and carrying a locking device 50 adapted to lock the chain 5 against movement in one direction to prevent the door from being opened by hand and at the same time permit free movement of the chain 5 in the opposite direction to enable the door 55 to be closed by hand should occasion arise for so doing, as for instance should the door be left open slightly, say an inch or so by the mechanism of the car 20. The guide 21, which may be constructed in any desired 60 manner is preferably formed by bending 65

the outer edge of the support back on itself to embrace partially the chain 5 and retain the outer vertical stretch or run 13 in mesh with a sprocket wheel 22, which constitutes a portion of the locking device. The 70 sprocket 22, which is mounted on a suitable shaft or spindle 23, is provided at its outer side face with a ratchet wheel or portion 24, which is normally engaged by a spring actuated pawl or dog 25. The pawl 75 or dog 25 is pivoted at a point intermediate of its ends to the support or member 17 by a pin or rivet 26, and a spring 27 urges its engaging end in the direction of the ratchet wheel 24. The other end of the pawl 25 80 which is located near but slightly above the lower projection 19 is arranged in the path of the motor actuated mechanism of the car or cage and is engaged by such motor actuated mechanism an instant prior 85 to the engagement of the said lower projection 19 by the mechanism of the car 20 so that the chain 5 will be released by the locking device before motion is imparted to the said chain 5 to open the elevator inclosure 90 door. As soon as the pawl or dog 25 is relieved of the pressure of the coacting mechanism of the car it automatically under the action of the spring 27 reengages the ratchet teeth 24 of the sprocket wheel 95 22. When the pawl 25 is in engagement with the ratchet element 24 of the sprocket wheel the outer vertical stretch or run 13 is locked against upward movement but is permitted free downward movement to enable the door 1 to move toward its closed position without permitting the door to move in the direction of its open position.

The mechanism of the car comprises a vertically slideable shoe or traveler 28 guided by spaced parallel rails 29 and actuated by an electric motor 30 or other suitable power. The traveler 28 which may be of any preferred construction is shown in the accompanying drawings as consisting of spaced 105 horizontal bars having projecting terminal portions 31 arranged at the opposite faces of the guide rails 29 and receiving the same between them and slideable thereon. At the outer side the traveler 28 has a projecting 110 engaging portion 32 which is guided by the rails 29 into the space between the projections 18 and 19 of the support or member 17 of the door moving mechanism and which is adapted to engage the lower projection 19 115 to move the endless chain 5 in the proper direction to open the door 1. In the arrangement illustrated in the accompanying drawings the downward movement of the support or member 17 opens the door and 120 the reverse or upward movement caused by the engagement of the traveler 28 with the upper projection 18 closes the door.

The traveler or shoe 28 is clamped by connecting bolts 33 to a pair of spaced parallel 125

endless flexible connections 34, such as cords, cables, belts, chains or analogous devices encircling the car or cage 20 at the front, back, top and bottom and guided by 5 suitable pulleys or sheaves 35 located at the top and bottom of the car or cage 20. Endless cords 34 are preferably employed and they are operatively connected with the motor preferably by being wrapped one or 10 more times around a drum 36 on the motor shaft 37, whereby when the motor shaft 37 is rotated the endless cords 34 will be wound on and unwound from the drum 36 and thereby set in motion. Any other suitable 15 means may be employed for operatively connecting the endless cords with the motor 30 which is designed to be controlled by push buttons 38 or other switches arranged in convenient position within the car or cage 20 within convenient reach of the operator.

When the motor circuit is closed motion is imparted to the endless cords 34 which are caused to travel over the pulleys 35 and slide the shoe or traveler along the guide rails 29. 25 The guide rails 29 which may be constructed of any suitable material, are mounted on the car or cage 20 at the front thereof and they extend downwardly from the top of the car 20 a suitable distance and are 30 provided at the top of the car with substantially sigmoidal guiding bends 39 extending inwardly and upwardly over the top of the car and adapted to guide the shoe or traveler inwardly out of engagement with the 35 upper projection 18 of the member or support 17 as the latter reaches the limit of its upward movement, the traveler disengaging itself from the upper projection 18 when the elevator door 1 has about reached its 40 closed position. The momentum of the door 1 completes the closing movement of the door and carries the upper projection 18 slightly above the point where the traveler disengages itself from the said projection 18 45 so as to leave sufficient space for the traveler in its downward movement to pass beneath the upper projection and move downwardly into engagement with the lower projection 19 to open the door 1.

50 The inwardly offset guiding portions or bends 39 of the rails are located slightly below and in front of the dome 42 of the car or cage 20, ample space being provided at the top of the car or cage 20 and the motor 30 being preferably mounted upon the cross-head 43 of the car 20, but the motor 30 may be mounted on any other convenient portion on the car and the endless cords 34 may be arranged in any other suitable manner to 55 effect the sliding of the traveler along the guiding rails. Also, any other means may be employed for operatively connecting the traveler with the actuating motor and the cords 34 are also susceptible of operation 60 by hand.

The door operating apparatus of the present invention is designed principally for use in connection with electrically controlled elevators and in practice a suitable switch 44, connected with the operating circuit 45 of the elevator will be arranged in the path of the traveler to cause the latter to close the operating circuit when the door 1 is closed and to open the operating circuit and prevent the car or cage from being started 70 while the door is open. The automatically operating switch 44 may be connected by wires 46 and 47 with the jumper wire 48 extending from the safety switch 49 to the operating switch 50.

The spaced upper and lower projections 18 and 19 have flat upper and lower faces, respectively, and are adapted to prevent a careless or inexperienced operator from stopping his car too far above or below a 85 floor or landing and opening the inclosure door. For instance, if the operator should bring his car to a stop too far above a landing the engaging portion of the traveler would be guided into the plane of the upper 90 projection 18 at a higher elevation than the said projection 18 and its downward movement would come in contact with the flat upper face of the projection 18 and would be arrested in its downward movement and 95 prevented from entering the space between the projections 18 and 19 and engage the lower projection 19 and open the door. On the other hand, if he should stop his car too far below the floor or landing the engaging 100 portion of the traveler would miss the lower projection and could not open the door.

In practice, the projections 18 and 19 will be placed about 8 inches apart, which will be sufficient to allow the operator to 105 stop his car two or three inches above or below a floor or landing and open the inclosure door as there will be sufficient distance between the projections 18 and 19 to permit the engaging portion of the traveler to enter the space between them and 110 actuate the door moving mechanism. This space may be regulated in the construction of the support or member 17.

Having thus fully described my invention 115 what I claim as new and desire to secure by Letters Patent is:

1. In an elevator, a plurality of doors to be moved, a car, a motor carried by the car and adapted to move all of said doors one 120 at a time, means for controlling the motor and means operated by the motor for making a break in the operating circuit of the car prior to the actuation of a door and for closing such break after the door is closed. 125

2. In an elevator, a car, a plurality of doors to be moved, a normally inactive motor carried by the car, separate door moving devices for said doors including endless flexible connections having vertical and hori- 130

- zontal stretches at each door, the horizontal stretches being connected with the door, and means carried by the car and actuated by the motor and adapted to engage with the vertical stretch of each door moving device to impart motion to the same. 5
3. In an elevator, a car, a plurality of doors to be moved, a motor carried by the car, separate door moving devices including 10 endless flexible connections having horizontal and vertical stretches located at each door, the latter being connected with the horizontal stretch, a traveler moving upwardly and downwardly on the car and actuated by the motor and adapted to impart motion to the vertical stretches one at a time, and means for guiding the traveler into and out of open engagement with the vertical stretches. 15
4. In an elevator, a car, a plurality of doors to be moved, a motor carried by the car, separate door moving devices including endless flexible connections having horizontal and vertical stretches located at each 20 door, the latter being connected with the horizontal stretch, a traveler moving upwardly and downwardly on the car and actuated by the motor and adapted to impart motion to the vertical stretches one at a time, and guide rails mounted on the car and arranged to guide the traveler into and out of engagement with the vertical stretches. 25
5. In an elevator, a car, a plurality of doors, a motor mounted on the car, separate 30 door moving devices including flexible connections operatively connected with the doors and having a substantially vertical stretch at each door, and a traveler actuated by the motor and movable upwardly and 35 downwardly on the car for actuating the vertical stretches. 40
6. In an elevator, a car, a plurality of doors, a motor mounted on the car, separate door moving devices including flexible connections operatively connected with the doors and having a substantially vertical stretch at each door, a flexible connection mounted on the car and operatively connected with and actuated by the motor, and 45 mechanism operated by the flexible connection of the car for actuating the said vertical stretch of the door moving device. 50
7. In an elevator, a car, a plurality of doors, a motor mounted on the car, separate door moving devices including flexible connections connected to the doors, a flexible connection carried by the car and operatively connected with the motor and coacting means for connecting the flexible connection of the car with the flexible connections of the door moving devices one at a time for opening and closing the doors. 55
8. In an elevator, a plurality of doors to be moved, a car, a motor carried by the car and independent of the movement thereof, 60 separate door moving devices for said doors including an endless flexible connection consisting of a horizontal portion extending along the top of said doors and a substantially vertical portion arranged at one side 70 of the doors, a flexible connection mounted on the car and operatively connected with the motor and having a substantially vertical portion, and coacting means for connecting the said vertical portions of the flexible 75 connections with each other to enable the motor to actuate the doors one at a time. 75
9. In an elevator, a plurality of doors to be moved, a car, a motor carried by the car and independent of the movement thereof, 80 separate door moving devices for said doors including an endless flexible connection consisting of a horizontal portion extending along the top of said doors and a substantially vertical portion arranged at one side 85 of the doors, an endless flexible connection carried by and passing around the car and operatively connected with the motor, and coacting means for connecting the flexible connection of the car with the flexible connection of the door moving devices to actuate the doors one at a time. 90
10. In an elevator, a plurality of doors to be moved, a car, a single motor mounted on the car and independent of the movement thereof, a separate door moving device for each door including a flexible connection operatively connected with its respective door and having a vertical portion provided with spaced projections, a traveler movable vertically on the car and actuated by the motor, and means for guiding the traveler into and out of the space between the projections, which are engaged by the traveler to actuate the doors one at a time. 95
11. In an elevator, a plurality of doors to be moved, a car, a single motor mounted on the car and independent of the movement thereof, a separate door moving device for each door including a flexible connection operatively connected with its respective door and having a vertical portion provided with spaced projections, a traveler movable vertically on the car and actuated by the motor, and a vertical guide mounted on the car and 100 having an offset portion, said guide being arranged to guide the traveler into and out of the space between the said projections, which are engaged by the traveler to actuate the doors one at a time. 105
12. In an elevator, a plurality of doors to be moved, a car, a motor mounted on the car and independent of the movement thereof, a separate door moving device for each door including a flexible connection operatively connected with its respective door and having a vertical stretch provided with spaced 110 projections, a vertical guide rail mounted on the car and having an offset portion at one end, and a traveler operatively connected with the door moving device. 115
13. In an elevator, a plurality of doors to be moved, a car, a motor carried by the car and independent of the movement thereof, a separate door moving device for each door including a flexible connection operatively connected with its respective door and having a vertical stretch provided with spaced 120 projections, a vertical guide rail mounted on the car and having an offset portion at one end, and a traveler operatively connected with the door moving device. 125
14. In an elevator, a plurality of doors to be moved, a car, a motor carried by the car and independent of the movement thereof, a separate door moving device for each door including a flexible connection operatively connected with its respective door and having a vertical stretch provided with spaced 130 projections, a vertical guide rail mounted on the car and having an offset portion at one end, and a traveler operatively connected with the door moving device. 130

5 neeted with the motor and movable along the guide rail into and out of the space between the said projections and also slidable along the guide rail to engage the said projections to actuate the doors one at a time.

13. In an elevator, a plurality of doors to be moved, a car, a single motor mounted on the car and independent of the movement thereof, a separate door moving device for each door including a flexible connection positively connected with its respective door and having a vertical portion provided with projecting means, a vertical guide rail mounted on the car and having an offset portion at the top, including a flexible connection positively connected with its respective door and having a vertical portion provided with projecting means, a vertical guide rail mounted on the car and having an offset portion at the top, and a traveler operatively connected with the motor and slidable along the guide into and out of engagement with the said projecting means and adapted to actuate the same to open and close the doors one at a time.

14. In an elevator, a plurality of doors to be moved, a car, a motor mounted on the car and independent of the movement thereof, a separate door moving device, for each door, including a flexible connection operatively connected with its respective door and having a vertical portion provided with projecting means, a movable traveler mounted on the car and operatively connected with the motor and arranged to engage the said projecting means to move the doors one at a time, and means automatically released by the traveler for locking the doors against movement in one direction and for permitting movement of the same in the opposite direction when the traveler is at rest.

15. In an elevator, a plurality of doors to be moved, a car, a motor mounted on the car and independent of the movement thereof, a separate moving device for each door including a flexible connection operatively connected with its respective door and having a vertical portion, spaced vertical guide rails mounted on the car, a traveler operatively connected with the motor and slidably mounted on the guide rails and movable along the same while the car is stationary to engage and actuate the said vertical portion of the flexible connection.

16. In an elevator, a plurality of doors to be moved, a car, a motor mounted on the car and independent of the movement thereof, a separate moving device for each door including a flexible connection operatively connected with its respective door and having a vertical portion, spaced vertical guide rails mounted on the car, a traveler operatively connected with the motor and slidably mounted on the guide rails and movable

along the same while the car is stationary to engage and actuate the said vertical portion of the flexible connection said guide rails having their upper portions curved inwardly at the top of the car to guide the traveler into and out of engagement with the said flexible connection.

17. In an elevator, a plurality of doors to be moved, a car, a motor mounted on the car and independent of the movement thereof, a separate moving device for each door including a flexible connection operatively connected with its respective door and having a vertical portion, spaced vertical guide rails mounted on the car, a traveler operatively connected with the motor and slidably mounted on the guide rails and movable along the same while the car is stationary to engage and actuate the said vertical portion of the flexible connection said guide rails having their upper portions curved inwardly at the top of the car to guide the traveler into and out of engagement with the said flexible connection, and a circuit controller located in the path of the traveler and arranged to make a break in the operating circuit of the car prior to the actuation of a door and adapted to close such break in the said circuit after the door is closed.

18. In an elevator, a plurality of doors to be moved, a car, a motor mounted on the car and independent of the movement thereof, a separate door moving device for each door including a sprocket chain operatively connected with its respective door, a traveler actuated by the motor for imparting motion to the sprocket chain, a sprocket wheel meshing with the sprocket chain, and means for locking the sprocket wheel to hold the door in its closed position.

19. In an elevator a plurality of doors to be moved, a car, a motor mounted on the car and independent of the movement thereof, a separate door moving device for each door including a sprocket chain operatively connected with its respective door, a traveler actuated by the motor for imparting motion to the sprocket chain, a sprocket wheel meshing with the sprocket chain, and means for locking the ratchet wheel against movement in one direction and for permitting movement in the opposite direction, whereby the door is held against opening and is permitted movement toward its closed position.

20. In an elevator, a plurality of doors to be moved, a car, a motor mounted on the car and independent of the movement thereof, a separate door moving device for each door including a sprocket chain operatively connected with its respective door, a traveler operatively connected with the motor and arranged to actuate the sprocket chain, a sprocket wheel meshing with the sprocket chain, and means for locking the sprocket wheel comprising a ratchet wheel and a pawl.

arranged to be automatically released by the traveler.

21. In an elevator, a plurality of doors to be moved, a car, a separate door moving device for each door including a flexible connection operatively connected with its respective door and having spaced stretches movable in opposite directions, a rotary element carried by one of the stretches and 10 meshing with the other stretch, means for locking the rotary element and means on the car for releasing the flexible connection from the locking device and for actuating the flexible connection.

15 22. In an elevator, a plurality of doors to be moved, a car, a separate door moving device for each door including a sprocket chain operatively connected with its respective door and having spaced stretches movable 20 in opposite directions, a sprocket wheel meshing with one of the said stretches and carried by the other stretch, means comprising a pawl and ratchet for locking the sprocket wheel, and means carried by the 25 car for releasing the sprocket wheel and for actuating the sprocket chains.

23. In an elevator, a plurality of doors to be moved, a car, a separate door moving device for each door in a flexible connection 30 operatively connected with its respective door and having spaced stretches movable in opposite directions a support carried by one of the said stretches and having a guide receiving the other stretch, means mounted 35 on the support for locking the flexible connection to hold the door closed, and means carried by the car for releasing the flexible connection and for actuating the same.

24. In an elevator, a plurality of doors to 40 be moved, a car, a separate door moving device for each door including a flexible connection operatively connected with its respective door and having spaced stretches movable in opposite directions, a support 45 carried by one of the said stretches, a rotary element mounted on the support and meshing with the other stretch, a ratchet wheel connected with the said rotary element, a pawl engaging the ratchet wheel and means mounted on the car for operating the pawl to release the rotary element and for actuating the flexible connection.

25. In an elevator, a plurality of doors to be moved, a car, a single motor mounted on

the car, a drum connected with the motor, a 55 pair of flexible connections guided on the car and actuated by the drum, a traveler carried by the flexible connections, a separate door moving device for each door including a flexible connection operatively connected 60 with its respective door and having projecting means to engage with the traveler, and means carried by the car for guiding the traveler into and out of engagement with the said projecting means.

65 26. In an elevator, a car, a plurality of doors to be moved, a separate door moving device for each door including a vertically movable member, flexible connections operatively connecting the said movable member 70 with its respective door, and actuating mechanism on the car comprising a vertically movable traveler adapted to engage with the said member and means for raising and lowering the traveler.

75 27. In an elevator, a car, a plurality of doors to be moved, a separate door moving device for each door including a vertically movable member, flexible connections operatively connecting the said movable member 80 with its respective door, and actuating mechanism on the car comprising a vertically movable traveler adapted to engage with the said member and means for raising and lowering the traveler, and locking means for the 85 door moving devices automatically released by the mechanism of the car.

28. In an elevator, a car, a plurality of doors to be moved, a separate door moving device for each door including a vertically 90 movable member, flexible connections operatively connecting the said movable member with its respective door, and actuating mechanism on the car comprising a vertically 95 movable traveler adapted to engage with the said member, means for raising and lowering the traveler, and locking means for the door moving devices automatically released by the mechanism of the car, said locking means permitting the door to move in one 100 direction and holding the same against movement in the opposite direction.

In testimony whereof I affix my signature in presence of two witnesses.

THOMAS A. HOLLORAN.
